UNITED STATES PATENT OFFICE.

ADOLPHE ANTOINE FRANÇOIS MARIUS SEIGLE, OF PARIS, FRANCE.

APPARATUS FOR TRANSFORMING AND DISTILLING HYDROCARBONS AND THE LIKE.

Application filed July 16, 1920. Serial No. 396,767.

To all whom it may concern:

Be it known that I, ADOLPHE ANTOINE FRANÇOIS MARIUS SEIGLE, citizen of the Republic of France, residing at 3bis Rue 5 Clément Marot, Paris, in the Republic of France, have invented new and useful Improvements in Apparatus for Transforming and Distilling Hydrocarbons and the like, of which the following is a specification.

This invention relates to improved means for heating hydrocarbons to any desired degree, the heating of the hydrocarbons being effected, if desired, in the presence of certain solid substances to obtain simply the distillation, or thermo-chemical reactions between the constituent elements of the material to be treated, and subjected to the methodical action of the more or less intensive heat at determined temperatures. Said means may also be employed for treating any other liquid or gas.

The invention comprises a retort consisting of one or more hollow elements of cast iron, bronze, steel or of any appropriate material capable of withstanding intense heat as it will be described hereinafter.

The entire apparatus may be arranged either horizontally, or vertically, or in an inclined position, and is fixed upon a frame.

The accompanying drawings illustratively exemplify the invention as used for the treatment of hydrocarbons:

Fig. 1 is a longitudinal section of a retort.

Fig. 2 is a cross section thereof along the line $d-d'$, Fig. 1.

Fig. 3 is a cross section thereof along the line $c-c'$, Fig. 1.

Fig. 4 is a detail in cross section of a plug for said retort.

Figs. 5 and 6 are elevation views of the openings provided in the wall of the retort.

Fig. 7 is a diagrammatic view of a complete installation according to the invention.

The retort according to this invention consists of several elements having the form of a prism or a hollow or solid cylinder or like form and inside which is provided a coil shaped conduit having circulating therein the hydrocarbons or other material under treatment.

In the example shown, the retort B is com-

posed of three drum members A², B², C², which are placed end to end and one upon the other if the retort is arranged vertically or in an inclined position. Each member has a central conduit or furnace formed 60 therein to permit of an intensive heating, said conduits having unequal and gradually increasing diameters. Between the inner wall and the external wall of each drum is left an annular space which is divided by 65 cross partitions connecting the two walls into five annular passages e e' stopped by a longitudinal partition u and placed in communication by means of orifices r situated alternately on each side of the partition u, so as to form a coil shaped conduit.

In the outer wall of each of the three drums are disposed three elongated rectangular openings x, y, z (Fig. 3) one of which (shown at the top of Fig. 3 and in front 70 view in Fig. 5), shows the partition u at its middle part. These openings give access to the interior of the annular passages e e' for inspection and cleaning of the latter when desired or for disposing therein at 75 certain points metal straw or turnings (iron, aluminum, etc.) granulated metal or the like adapted to aid in the treatment of the hydrocarbons or the like.

The said orifices are normally closed by 80 stoppers having the same form (Fig. 4) held in place by bolts or by arches closing members whereby they can be easily removed and replaced.

The drums A², B², C² which are situated 85 in line and along a common axis, are connected together at the ends by six cylindrical tenons g (Figs. 1 and 2), one of which is hollow and effects communication between the coil portion of the adjacent drums A², 90 B², C² which are however separated by the space d d' (Fig. 1).

The entire apparatus is mounted on its supporting frame by means of the base portions v (Fig. 3) forming part of the outer 100 envelopes and secured by bolts or screw spikes.

The retort which has just been described is operated in the following manner.

The cheap liquid fuel which is used for 105 heating is delivered into a pressure tank A (Fig. 7) by the pipe a. The fuel passes through pipe a' into a gasifying apparatus A' of a standard type, which may be replaced either by a steam or compressed 110

air atomizer or by a plurality of suitable burners supplied with producer gas or the like.

Atmospheric air is automatically introduced (as shown by the curved arrows 1) through the spaces d d' (Fig. 1) and produces a greater or less degree of heat in the retort according to the force of projection and the density of the stream of flame.

10 The powerful flame or flames thus produced are directed according to the arrows 2 (Figs. 1 and 7) into the central conduit or furnace of the retort B described above, which is mounted upon a frame b . As previously stated, said retort may be arranged either horizontally as shown, vertically or in an inclined position.

15 The hydrocarbon or other liquid or gas which is to be treated is delivered into the coil conduit e , e' through the orifice f (Fig. 1) and passes successively through the entire series of circumvolutions or inner passages of the three drums, being discharged at the other end f' of the coil passage after 20 having followed the general direction shown by the arrows 5 (Figs. 1 and 7) and being submitted to a gradually increasing heating action, the material being treated preferably circulating in a direction opposite 25 to that of the heating gases. The heated and heating gases might circulate in the same direction, if necessary, but this would be less desirable.

30 The burning gases which leave the heating conduit of the retort B will travel in a zigzag path (Fig. 7) through the double rectangular chamber of a recuperator of heat, wherein they pass according to the arrows 3 and 4 and they will be successively 35 cooled upon the outer walls of the two heat exchanging members C and O until they are finally discharged into the atmosphere through the stack P.

35 In the case of the distillation of hydrocarbons metal turnings placed in the coil conduit are extremely advantageous. They will divide and so to speak laminate into very fine streams the hydrocarbons and already more or less gasified vapor produced 40 in the first portion of this circulation, and the well known action of superheating upon the hydrocarbon vapors now becomes much stronger for a given temperature and also sufficiently easy to regularize. On the other 45 hand since the iron and aluminum turnings have an active though small capacity for ab-

sorption of atoms of carbon and hydrogen at the respective temperatures of 650° and 450° C., this will afford another cause for the rupture of chemical equilibrium of the hydrocarburated molecules, which cause of rupture will be added in an efficacious manner to that resulting from the methodical superheating to whose effects these same molecules are subjected at the said respective temperatures by reason of the successive passage of the same through the layers of aluminum turnings at about 450° and then through the layers of iron turnings at about 650° C.

45 However, as is well known to specialists, "all systems in chemical equilibrium will be definitely transformed by reason of the variation of a single one of the factors of this equilibrium such as pressure, temperature, electro-motive force or concentration of the bodies under reaction," said transformation in the present case causes an energetic heightening of the decarburation and the depolymerizm of the molecules 50 in question.

55 The residuum which remains within the retorts, in the case represented in Fig. 7, is evacuated by means of a collecting drain pipe (not shown) into which all the tar at the lower part of each element is discharged. The drain pipe is provided with a drain cock which is opened at intervals.

60 Having now described my invention, what I claim as new and desire to secure by Letters Patent is:

65 Apparatus for treating hydrocarbons and the like comprising a retort having a hollow cylindrical wall, a second hollow cylindrical wall spaced therefrom and concentric therewith, spaced annular transverse partitions between said two walls dividing the space between said walls into a series of annular chambers, a longitudinal partition between said two walls extending throughout the length of said walls, said transverse partitions having apertures situated alternately on opposite sides of said longitudinal partition whereby material to be treated may flow successively through each of said annular chambers in series and in alternately opposite directions, and means for heating the inner wall of said two walls.

70 In testimony whereof I have signed my name to this specification.

ADOLPHE ANTOINE FRANÇOIS MARIUS SEIGLE.
